UNITED STATES PATENT OFFICE.

JAMES S. WILKIN, OF HILLSBORO, OHIO.

WAVE-MOTOR.

1,369,593.

Specification of Letters Patent. Patented Feb. 22, 1921.

Application filed April 3, 1920. Serial No. 371,086.

To all whom it may concern:

Be it known that I, JAMES S. WILKIN, a citizen of the United States, residing at Hillsboro, in the county of Highland and 5 State of Ohio, have invented new and useful Improvements in Wave-Motors, of which the following is a specification.

The object of the invention is to provide a comparatively simple, relatively inexpensive and at the same time efficient and durable wave motor of a construction and arrangement of parts whereby a variation in 10 the turbulence of the water will have the minimum effect upon the operation of the mechanism to the end that the storage or 15 transmission of power will remain comparatively constant under all conditions and the liability of injury, if the apparatus is permitted to operate in stormy weather, will 20 be reduced as compared with those devices in which the float is subjected under all conditions to the full force of the wave motion, and with these objects in view the invention 25 consists in an apparatus of which a typical form is illustrated in the accompanying drawings, wherein:

Figure 1 is a general side view of the entire mechanism.

Fig. 2 is an enlarged front view, partly 30 broken away or in section of the motion transmission mechanism.

Fig. 3 is a rear or sea-ward elevation of the float and the means whereby the same is mounted.

Fig. 4 is a detail section on the line 4-4 of Fig. 2, and

Fig. 5 is a detail section on the line 5-5 of Fig. 2.

The float 10 consisting of a cross sectionally rhomboidal body having a forwardly and downwardly inclined oblique outer wall 11 and a forwardly and downwardly inclined bottom wall 12 (said body being of any desired length transversely of the direction of 40 movement of the wave, as suggested in Fig. 3) is supported by suitably braced arms 13, pivotally mounted at 14 upon standards 15 which also should be suitably braced and may consist of tiers or piles or may rise 45 as indicated in the drawing from a substantial platform 16, said float being so weighted so as to normally occupy a position which is about half submerged in the water when the latter is comparatively quiet, the normal 50 or neutral water-line being indicated at 17 and the construction of the body of the

float being such as to cause a deflection of the water as it encounters the body, to induce a glancing or deflecting impact so that the force of the waves will tend to raise the 60 body without imposing an objectionable strain upon the mountings of the supporting arms 13.

Carried by a suitable upright 18 located in convenient relation to the free edge of 65 the float are direction pulleys 19 and 20 around which extend a cable 21 which is attached as at 22 to the float, so that the upward and downward movements of the latter cause a reciprocatory running movement to the cable which at its landward end or bight passes around a sprocket wheel 23 forming a part of transmission mechanism which is suitably supported by a tower or 70 pier 24.

The said sprocket wheel carries clutch members 25 and 26 which are respectively arranged in coöperative relation with complementary clutch members 27 and 28 of which the former is keyed or otherwise 80 fixedly secured to the drive shaft 29 while the latter is loosely mounted upon said shaft and is provided with a beveled gear 30 meshing with a similar gear 31 which in turn is engaged with a gear 32 keyed or 85 otherwise secured to the drive shaft, to the end that rotary motion in either direction of the sprocket wheel, due to the movement of the cable or chain will communicate motion through one or the other of the 90 clutches to the drive shaft, but always will move the shaft in the same direction. Suitable bearings 33 and 34 are provided for the drive shaft and are supported by suitable pedestals 35 rising from the tower or 95 pier 24.

Owing to the peculiar construction and mounting of the float and the fact that under mean or normal conditions it is supported in what is approximately a semi-submerged condition, the walls of the float which are exposed to impact due to the wave movement of the water being disposed to deflect and thus minimize the impact of the water so that the effect upon the float is 100 mainly due to the rise and fall in the surface of the water, it is possible to use the transmission mechanism and supporting means for the apparatus which are of comparatively light structure without incurring 105 the risk, common to devices of this general type, of damage or serious injury in stormy

weather when the waves are relatively high and strong and in some instances necessitate the disconnection of the float or the elevation of the same to a level beyond the reach 5 of the waves. With the construction illustrated the apparatus may be used under all conditions and in practice is found to produce a power which is relatively constant and of moderate degree which can readily 10 be transmitted by mechanism of light and comparatively inexpensive structure.

What is claimed is:—

A wave motor comprising an upright support, landwardly extending arms pivoted upon the upper end of said support, a 15

float carried by the free ends of said arms and of rhomboidal shape whereby to present downwardly inclined oblique faces to an incoming wave, an upright support mounted at the free end of the float, a pulley journaled at the lower portion of said second named upright, a supporting structure spaced from the second named upright, a shaft journaled upon said last named supporting structure and carrying a fly-wheel, 20 ratchet mechanism and a pulley, and a flexible member trained about all of said pulleys and connected with the free end of the float.

In testimony whereof I affix my signature.

JAMES S. WILKIN.
